CLAIM

The ornamental design for a collapsible cup, as shown and described.

DESCRIPTION

FIG. 1 is a perspective view of a collapsible cup showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the collapsible cup in a second state;

FIG. 10 is a perspective view of the collapsible cup in a collapsed position; and,

FIG. 11 is an enlarged view of the collapsible cup shown within the area designated as 11 in FIG. 1.

The dash-dash broken lines in the drawing are for the purpose of illustrating portions of the collapsible cup that form no part of the claimed design. The dot-dash broken lines in FIG. 1 and FIG. 11 show a boundary of the enlarged view and form no part of the claimed design.
